UNITED STATES PATENT OFFICE.

GUSTAVE GLOCKER, OF NORTH EAST, MARYLAND.

KNOB-INSULATOR.

1,290,540.

Specification of Letters Patent.

Patented Jan. 7, 1919.

Application filed March 6, 1918. Serial No. 220,773.

To all whom it may concern:

Be it known that I, GUSTAVE GLOCKER, a citizen of the United States, residing at North East, in the county of Cecil and State 5 of Maryland, have invented a new and useful Knob-Insulator, of which the following is a specification.

This invention has reference to electric insulators of the knob and cap type, which 10 insulators are customarily made of porcelain, and its object is to provide an insulator permitting the cap and knob to be fired at the same time, with the cap in place on the knob, and also to provide for the clamping 15 of the electric conductor more securely than heretofore.

In accordance with the invention, the insulator has the body portion provided with conductor-receiving channels on opposite 20 sides of a diametric web, with the channels ribbed or roughened to hold the insulated conductor against slipping, the cap having a central boss or projection of a size to override the channels, and thereby provide 25 clamping means for the electric conductors, while the central rib of the body portion of the knob is recessed to receive the boss, thus holding the cap against displacement. That 30 end of the body or base portion of the knob opposite from the cap receiving end is countersunk and provided with an axial projection within the countersink extended close to but stopping short of the corresponding end of the knob base. The projection 35 serves to carry the cap by the central boss of the latter on introducing the coated knobs and caps in the furnace for firing them. These features render the insulator, 40 both in the matter of manufacture and use, advantageous over similar insulators as heretofore made.

The invention will be best understood from a consideration of the following detailed description, taken in connection with 45 the accompanying drawing forming part of this specification, with the further understanding that, while the drawing shows a practical form of the invention, the latter is not confined to any strict conformity with 50 the showing of the drawing but may be changed and modified so long as such changes

and modifications come within the scope of the appended claims.

In the drawing:

Figure 1 is an elevation of the insulator 55 knob and cap;

Fig. 2 is a central diametric section cutting across the conductor-receiving channels;

Fig. 3 is a section on the line 3—3 of 60 Fig. 1;

Fig. 4 is a view of the conductor-engaging face of the cap;

Fig. 5 is a view of the conductor-engaging 65 face of the body of the knob.

Fig. 6 is a longitudinal section of the knob base and cap as associated for firing.

Referring to the drawings, there is shown a knob comprising a body member 1 and a cap 2, such knob being customarily of cylindrical conformation, and is made of earthenware material, ordinarily known as porcelain, and has the exposed surface glazed.

The body member or base 1 and the cap 2 are formed with central longitudinal matching channels 3 and 4 respectively, with the channel 4 at that face of the cap 2 remote from the body member 1 countersunk, as shown at 5, so that a screw or nail may be utilized for fastening the insulator knob in 80 place.

On opposite sides of a diameter of the body member or base 1 at the conductor-engaging face thereof, are channels 6 of sufficient width to lodge an insulated electric 85 conductor of customary size. The channels 6 are spaced apart sufficiently to leave a diametric rib 7 having its intermediate portion recessed or cut away, as shown at 8, so that the terminal portions of the rib or web 90 7 are on the same level as the remainder of the corresponding end of the body portion 1, such end being substantially flat. Between the outer sides of the grooves 6 and the margins of the body member 1, are 95 ledges 9 in the same plane as the ends of the rib 7.

The grooves 6 have each a series of laterally disposed projections 10 forming teeth or gripping means for engaging the insulation covering of the conductor lodged in the groove, and so prevent slipping of the 100

conductor without necessitating excessive pressure in clamping the conductor.

The cap 2 is in the form of a cylindrical block, with that face designed to engage the body member 1 provided with a circular flat boss 11, with the face remote from the cap having an annular series of teeth or projections 12, radiating from a ring 13 surrounding the passage 4. The projections 12, like the teeth or projections 10 in the grooves 6, extend away from the cap only sufficiently to form a roughened or gripping surface to engage the insulation covering the conductor seated in a groove 6 to hold the latter against slipping through the insulator, without, however, any injury to the insulation.

The depression 8 in the rib 7 is of a length but little longer than the diameter of the boss 11. The boss 11 not only serves as an anchor to hold the cap on the body portion against displacement by forces incident to handling the knob structure when being placed into an oven to fire it, as will hereinafter appear, but the boss serves as a clamping member for the conductor or conductors lodged in the groove or grooves 6. In order to avoid any sharp points at the ends of the grooves 6, said ends of the grooves are expanded, as indicated in the drawings.

At that end of the basic portion of the knob remote from the one designed to receive the cap 2 is a countersink 14 within which there is produced an axial projection 15 extending close to but not reaching the outer end of the countersink 14. The length of the projection 15 is such that when the parts are first molded and before firing, the boss 11 will enter the countersink 14 and rest upon the projection 15 with the boss partly within the countersink 14.

When the knobs are placed in the furnace for firing, the caps 2 rest upon the projections 15, the basic portions of the knobs being at the time inverted, with the projections 15 uppermost. The support for the caps 2 is relatively large, and the bosses 11 project sufficiently into the countersinks 14 to avoid liability of the caps being displaced in handling. At the same time, the caps are raised sufficiently above the knob bases to avoid any danger of the glazing material of the caps and knob bases uniting and so cementing the parts together. The result is that breakage or injury to the knobs during the firing operation is greatly reduced and practically eliminated.

The construction of the knob is advantageous in permitting the firing of the caps and bases together with little or no liability of injury because of the broad support of the cap on the projection 15 during firing, and when the parts are particularly liable

to breakage because of the friability of the material, and because the finished knob provides extensive gripping surfaces for the insulated conductors on opposite sides of the latter.

What is claimed is:—

1. An insulator knob for electric conductors comprising a body member having a diametric rib across one end with conductor-receiving grooves flanking said rib, and the rib being recessed lengthwise, and a cap for the grooved end of the body member, said cap having an intermediate flat boss projecting from the face designed to engage the grooved end of the body member, the boss being of cylindrical shape, and of a diameter to enter the recess in the rib and extend across the grooves on opposite sides of the rib.

2. An insulator knob for electric conductors comprising a body member having a diametric rib across one end with conductor-receiving grooves flanking said rib, and the rib being recessed lengthwise, and a cap for the grooved end of the body member, said cap having an intermediate flat boss projecting from the face designed to engage the grooved end of the body member, the boss being of cylindrical shape, and of a diameter to enter the recess in the rib and extend across the grooves on opposite sides of the rib, both the grooves and the boss having shallow teeth or projections for engaging a conductor or conductors lodged in the groove or grooves.

3. An insulator knob for electric conductors comprising a body member having a diametric rib across one end with conductor-receiving grooves flanking said rib, and the rib being recessed lengthwise, and a cap for the grooved end of the body member, said cap having an intermediate flat boss projecting from the face designed to engage the grooved end of the body member, the boss being of cylindrical shape, and of a diameter to enter the recess in the rib and extend across the grooves on opposite sides of the rib, both the grooves and the boss having shallow teeth or projections for engaging a conductor or conductors lodged in the groove or grooves, and the teeth or projections in the grooves extending transversely of the length of the latter, with the teeth or projections in the boss arranged radially thereof in circular series.

4. An insulator knob for electric conductors comprising a body member countersunk at the basic end and there provided with an axial extension stopping short of the basic end of the body member, and a cap member with an axial flat boss of greater axial length than the free end of the projection within the countersink and the corresponding end

of the body member, whereby the body member and cap member may be fired together, with the cap member sustained by the projection of the body member, and the boss of 5 the cap member entering the countersink in the body member to an extent less than the axial length of the boss.

In testimony, that I claim the foregoing

as my own, I have hereunto affixed my signature in the presence of witnesses.

GUSTAVE GLOCKER.
